KEYBOARD MECHANISM FOR PRINTING TELEGRAPH APPARATUS

Filed Sept. 20, 1929

UNITED STATES PATENT OFFICE

HOWARD L. KRUM, OF KENILWORTH, ILLINOIS, ASSIGNOR TO TELETYPE CORPORATION,
OF CHICAGO, ILLINOIS, A CORPORATION OF DELAWARE

KEYBOARD MECHANISM FOR PRINTING TELEGRAPH APPARATUS

Application filed September 20, 1929. Serial No. 394,067.

The invention relates to permutation keyboard mechanisms in which a plurality of keys are arranged to position a set of permutation elements in different combinations. 5 Such keyboards are employed principally in telegraph systems for transmitting signals or perforating tape in accordance with a code made up of permutations of a definite number of two different conditions. In such 10 apparatus, each key represents a particular character or code signal and is arranged to effect the setting of a set of permutation elements, one for each unit of the code, in a corresponding combination distinctive of the 15 particular character or signal.

In certain permutation keyboards now in use, a set of code bars are provided on their longitudinal edges with teeth having inclined cam edges, and each key lever is arranged to 20 engage the cam edges of the code bars to shift certain of the bars longitudinally in one direction and the others in the opposite direction, to thereby position the set of permutation elements in a characteristic combination. 25 Such keyboards can be rapidly operated since each key lever either positively advances or retracts all of the code bars, and springs which on account of friction of the parts may be slow-acting, are not depended upon to 30 store the code bars. Also, when any one key is depressed, such code bars serve to lock out the other keys. But the inclined cam edges of the teeth must be accurately formed, are liable to considerable wear due to rubbing 35 of the key levers thereon, and since the inclined cam edges tend to deflect the key levers laterally, an effective lock for preventing the simultaneous operation of two keys is not afforded in case the key levers spring or yield 40 laterally.

The present invention seeks to provide an improved permutation keyboard having the advantages of the keyboard above described, and which obviates the disadvantages. In 45 accordance with this improved keyboard, pairs of code bars are provided, one pair for each permutation element of the code, and each key is arranged to engage and move one of the bars of each pair transversely to there- 50 by either advance or retract the correspon-

ing permutation element. Also, connections are provided between the bars of each pair whereby the key-actuated movement of one bar will move the other in the opposite direction. With this arrangement, the permutation elements are positively positioned by 55 each key lever and, since the bars and operating levers all move in the same direction, their engaging edges can be at right angles, instead of inclined, to their paths of movement, 60 and wear on these parts is thus avoided. Furthermore, the arrangement affords a good lock-out for preventing the operation of more than one key lever at a time, and such locking is not affected by the lateral springing 65 or movement of the key levers and bars, so that the latter can be inexpensively formed of thin sheet metal.

The invention consists in the foregoing and other features hereinafter set forth in detail, 70 illustrated in the preferred form in the accompanying drawing and more particularly pointed out in the appended claims. While, as stated, the present improvement can be applied to different keyboard transmitters, 75 perforators and the like, it is shown applied to mechanism for perforating tape in accordance with a code having six units or elements.

In the drawing:

Fig. 1 is a partial plan view of the essential elements of a perforator having the present improved keyboard mechanism. 80

Fig. 2 is a detail section on the line 2—2 of Fig. 1.

Figs. 3, 4 and 5 are enlarged detail views 85 of portions of the code bars shown in different positions.

Figs. 6 and 7 are detail sections on the lines 6—6 and 7—7 respectively, of Fig. 1.

Fig. 8 is a detail section on the line 8—8 90 of Fig. 2.

The perforator mechanism shown comprises a set of punches 10 movable through openings in upper and lower guide plates 11 95 and 12 and cooperating with a die plate 13 to perforate a tape 14, the plates 11 and 13 being spaced apart to form a tape guide. The punches 10 are selectively operated by an actuating member or hammer 15 and a set of 100

permutation elements 16 corresponding in number to the punches 10.

The hammer 15 is arranged to oscillate upon a pivot 17 and forms the armature lever of a magnet 18. The selectors or permutation elements 16 are movable back and forth over the face of the actuating member or hammer 15, and are adapted to be positioned in different combinations with their outer ends either in advanced, operative positions beneath the corresponding punches, or in inoperative positions out of line with the punches. Upon each setting of the elements 16, the magnet 18 is energized and the actuator 15 oscillated to form a row of perforations in the tape corresponding to the setting of the elements. The punches are withdrawn from the tape by a spring-actuated stripper plate 19.

Also, each operation of the hammer 15 effects the operation of a punch 20, which forms a row of feed holes adapted to be engaged by the pin teeth of a feed wheel 21. The latter is provided with a ratchet wheel arranged to be engaged by a feed dog 22 which is pivoted on the end of the hammer or armature lever 15. A spring 23 connected to the feed dog serves both to hold the latter in engagement with the ratchet of the feed wheel, and also normally holds the armature lever against an adjustable stop 24. When the magnet is energized to effect the punching of a row of perforations in the tape, the armature lever is moved against a limiting stop 25 and the dog 22 moves idly over the teeth of its ratchet. When the magnet is de-energized, the punches are withdrawn from the tape by the stripper plate 19, and spring 23 restores the armature lever and dog 22 to their normal positions thereby advancing the feed wheel 21 and feeding the tape 14 one step.

The permutation elements 16 are set in different combination by a plurality of key levers 26 mounted on a pivot rod 27 and normally upheld in raised position by individual springs 28, the levers being provided, as usual, at their forward ends with keys 29 arranged in banks.

Beneath the key levers extend a number of pairs of code bars and, since in the form shown there are six permutation elements, a corresponding number of pairs of code bars are employed. Each pair comprises a bar *a* and a bar *b*, and these bars are all provided at one end with vertical slots or notches 30 which fit over spacing rollers 31 mounted on a shaft 32. The bars are thus held against longitudinal movement, but are free to be shifted vertically. At their opposite ends, the bars are formed with shallow notches 33 which extend over similar rollers 31 on a second shaft 32. These rollers simply serve as stops to limit the downward movement of the bars.

Pairs of rock arms 34 are pivotally mounted on the shafts 32 and one pair of rock arms is interposed between each pair of code bars, and the bars and arms are held in proper spaced relation by collars 35 mounted on the shafts 31. The rock arms 34 are substantially T-shaped or widened at their upper ends and are provided with offset lugs 36 on opposite sides of and spaced some distance from the pivot shaft. One of the lugs 75 of each rock arm projects forwardly into a notch on the lower edge of the corresponding code bar *a*, and its other lug projects rearwardly beneath the lower edge of the corresponding code bar *b*. With this arrangement, the depression of either bar of a pair rocks the arms and lifts the other bar.

Each pair of rock arms is pivoted to a longitudinally movable permutation bar 37 and, if desired, the latter could be connected directly to the corresponding selector or permutation element 16. But, in the form shown, the connections between the bars 37 and the elements 16 are effected by a plurality of levers 38 mounted on a pivot 39 and connected at their ends to the bars and elements. With this arrangement, the depression of any *a* bar of a pair of code bars will move the corresponding permutation element to its advanced or operative position, and will also lift the associated permutation bar *b*. Also, the depression of any *b* bar will lift the associated *a* bar and retract the corresponding permutation element to its inoperative position.

Each of the key levers 26 which extends across the code bars is arranged, when operated, to engage and depress one of the code bars of each pair and thereby set the same and the permutation bars or elements in a characteristic combination. Preferably, to effect this, the upper edges of the code bars are notched to provide high and low portions in accordance with the code. Also, the bars of each pair are complementary, that is to say, each bar is the opposite of its mate, the high portions of one bar of a pair being opposite the low portions in the other bar of the same pair. Thus, for example, the particular key lever shown in Fig. 6 is disposed above the high parts of and is arranged to depress the *a* bars of the first, second and sixth permutation elements, and the *b* bars of the third, fourth and fifth elements, and is disposed above low portions of the mates of these bars. With this arrangement, each key lever, when operated, can depress either an *a* or *b* bar of each pair, and lift the mate of each depressed bar, thereby advancing or retracting the corresponding permutation elements to positively position the same in a characteristic combination. In Fig. 3, a key is shown depressing an *a* bar, and in Fig. 4, a key is shown depressing a *b* bar.

Also, the connections between the bars of each pair, prevent the simultaneous complete depression of more than one key lever. If attempt is made to operate two key levers at the same time, they can only be depressed part way when they will be blocked by the high parts of the code bars, as shown in Fig. 5. The improved keyboard provides an effective lock-out; the permutation elements are all positively positioned by each key; inclined cam faces on the code bars which must be accurately formed are avoided; a wider margin of operation is attained; and the code bars and key levers which are formed of sheet metal strips arranged on edge, can be inexpensively manufactured and assembled. As the key levers only engage the horizontal edges of the high portions of each code bar, only these edges need be accurately formed, and, as such edges of each bar are in line, this can be readily effected.

For effecting the operation of the permutation elements, each key lever is arranged to depress a universal bar 40 which is mounted upon the pivot shafts 32 in the same manner as the code bars, and also cooperates with a pair of rock arms 34'. But this universal bar 40 has no mate, and the rock arms 34' have only forwardly projecting lugs extending beneath the bar 40. The lower ends of the arms are pivoted to a longitudinally movable bar 41 which is provided at its left-hand end with a restoring spring 42. In the form shown, bar 41, at its right hand end, has an insulating projection 43 which is arranged to engage one of a pair of normally open spring contacts 44 which are interposed in the circuit of the punch magnet 18. With this arrangement, whenever a key is depressed to set the permutation elements 16 in a particular combination, the contacts 44 are engaged to energize magnet 18 and effect the operation of the selected punches 10. When the key is released, the spring 42 opens the contacts and de-energizes the magnet. If attempt is made to depress two keys, as shown in Fig. 5, the bar 41 is not shifted far enough to engage the contacts.

As stated, the permutation elements could be connected directly to one of the pairs of code bars, but preferably, for convenience in compactly arranging the permutation elements, these parts are connected by the intermediate levers 38, the upper ends of which are offset and brought closer together as shown in Fig. 8.

Instead of storing the character signals in a perforated tape, the code bars could be arranged to selectively condition contacts or contact controlling means of a keyboard transmitter, such as shown for example in the H. L. Krum U. S. Patent No. 1,595,472, to effect the direct transmission of the signals. In this case, the universal bar 40 would control the operation of the distributor of the

transmitter. Other changes could be made without departure from the scope of the appended claims.

I claim as my invention:

1. In a telegraph keyboard mechanism, a set of elements, corresponding pairs of code bars for conditioning said elements in different combination, and a plurality of keys, each arranged to move the bars of every pair transversely of their lengths in opposite directions and selectively condition all of said elements. 75

2. In a permutation keyboard for telegraph apparatus and the like, a set of elements to be conditioned in different combinations, corresponding pairs of code bars movable transversely of their lengths to position, the corresponding element in either one of two positions, and a plurality of key levers each arranged to move one bar of every pair 85 in one direction and the other in the opposite direction to positively position all of said elements. 85

3. In a permutation keyboard, a set of elements, corresponding pairs of code bars for 90 conditioning said elements in different combinations, and a plurality of keys, each arranged to move the bars of every pair transversely of their lengths in opposite directions and selectively condition all of said 95 elements, the bars and elements being arranged to retain the setting effected by any key until the same is changed by the operation of another key. 100

4. In a keyboard mechanism for telegraph apparatus and the like, pairs of complementary code bars, one pair for each element of a code, and a plurality of key levers each arranged to positively move the bars of every pair transversely of their lengths in opposite directions and thereby selectively condition all said code bars. 105

5. In a permutation keyboard, a set of horizontally disposed, vertically movable code bars, arranged in pairs, a plurality of horizontally disposed vertically movable, key-actuated levers extending transversely of and in one-way engagement with the code bars and each arranged to engage and move one of the bars of each pair, means interposed between each pair of bars for moving either bar in the one direction when the other is engaged and shifted in the opposite direction by a key lever, and a set of elements each positively moved in opposite directions by the bars of one of said pairs. 115 120

6. In a permutation keyboard, a set of permutation elements, a set of horizontally disposed vertically movable code bars operatively connected to said elements and arranged in pairs, one pair for each element, the bars of each pair having complementary notched edges and connections for compelling their vertical movement in opposite directions and for maintaining one bar in its raised and 125 130

the other in its depressed position, and a plurality of key-actuated levers each arranged to engage the notched edge of one bar of every pair to depress the same and position said permutation elements in different combinations.

7. In a permutation keyboard, a set of longitudinally movable permutation bars, corresponding pairs of code bars, one pair for each of said permutation bars, connection 10 between the code bars of each pair and the corresponding permutation bar for compelling the movement of the code bars of each pair transversely of their lengths in opposite directions and lengthwise movement of the corresponding permutation bar in opposite directions, each pair of code bars having complementary notched edges and a plurality of key-operated levers movable transversely of their lengths and in the same direction as said code bars, each of said levers being arranged 15 to engage the notched edge of one of the code bars of each pair to thereby positively position all of the code and permutation bars in different combinations, said bars being in 20 normal position and arranged to retain their setting until the same is changed by the operation of a key lever.

8. In a permutation keyboard for telegraph apparatus, a set of permutation elements, a plurality of vertically movable key levers, and horizontally disposed code bars engaged and shifted vertically by said key levers to positively set all of said elements, each in either one of two positions, said elements being arranged to retain the setting effected by a key lever until the same is 25 changed by the operation of another key.

9. In a permutation keyboard, a set of horizontally disposed code bars, arranged in pairs, one pair for each element of a code, a plurality of vertically movable, key-operated levers arranged to engage said bars and move the same vertically and transversely of their lengths in different combinations, and connections between the bars for each 30 pair for compelling their vertical movement in opposite directions and for preventing the complete simultaneous operation of two or more key levers.

10. In a permutation key board, a set of code bars arranged in pairs, one pair for each element of a code, the bars of each pair being connected for transverse movement in opposite directions, and a plurality of key levers, each arranged to engage the longitudinal edge of one bar of every pair to positively 35 position the bars in a predetermined combination, the lever-engaged edges of said bars being substantially at right angles to the paths of movement of the levers.

11. In a permutation keyboard, a set of horizontal, sheet metal code bars disposed on edge and arranged in pairs with connections between the bars of each pair for compelling

their vertical movement in opposite directions, and a plurality of sheet metal key levers disposed on edge and extending across said code bars, each key lever being arranged to engage and thereby shift one of the bars of every pair to positively position the same in a pre-determined combination, the engaging edges of said bars and key levers extending substantially at right angles to the directions of movement thereof.

12. In a permutation keyboard, a set of transversely movable code bars arranged in pairs, one pair for each element of a code, a pair of rock arms mounted on fixed pivots associated with each pair of code bars and arranged to be engaged and shifted in opposite directions respectively by the bars of the corresponding pair, a set of longitudinally movable permutation bars, one connected to each pair of rock arms, and a plurality of key levers, each arranged to engage and thereby shift one of the code bars of every pair and thereby positively position said permutation bars in a corresponding combination.

13. In a keyboard mechanism, a set of horizontally disposed code bars arranged in pairs, the bars of each pair being connected for transverse vertical movement in opposite directions and having complementary notched upper edges, and a plurality of vertically movable key levers extending across said code bars and each arranged to engage the edges of a high portion of one of the bars of every pair to positively position all of the bars in a corresponding combination.

14. In a keyboard mechanism, a number of pairs of horizontal, vertically movable code bars with the bars of each pair adjacent each other, a pair of vertically disposed rock levers mounted on fixed pivots interposed between the bars of each pair and engaging the same adjacent their ends to compel their vertical movement in opposite directions, said bars having complementary notched edges with the edges of the high portion extending in horizontal planes, and a plurality of vertically movable key levers extending across said bars and each arranged to engage a high portion of one bar of every pair to 105 depress the same.
